MOPHEAD WITH QUICK RELEASING
MOP CLAMP

Frank E. Nezamis, Kalamazoo, Mich.

Application October 20, 1947, Serial No. 780,781

2 Claims. (Cl. 15—153)

1

This invention relates to improvements in mop head with quick releasing mop clamp.

The principal objects of this invention are:

First, to provide a novel form of mop head which is easily opened to free the mop therefrom.

Second, to provide a mop head of sturdy inexpensive construction which will tightly grip a mop.

Third, to provide a mop head with simple clamping members which can be easily operated with the fingers even when the material of the mop is swollen or expanded as when wet.

Fourth, to provide an axially slideable mop supporting member for a mop head which may be locked in place to cooperate with a screw clamp and withdrawn axially for releasing the mop without first releasing the screw clamping member of the head.

Other objects and advantages pertaining to the details and economies of my invention will be apparent from a consideration of the following description and claims.

The drawings, of which there is one sheet, illustrate a preferred form of my mop head.

Fig. 1 is an elevational view of my mop head in open or unclamped position and partially broken away in transverse cross section.

Fig. 2 is a vertical cross sectional view along the line 2—2 in Fig. 1 and shows a mop in operative clamped position in the mop head.

Fig. 3 is a transverse cross sectional view along the line 3—3 in Fig. 1.

Fig. 4 is a fragmentary vertical cross sectional view along the line 4—4 in Fig. 1.

My mop head consists of a frame generally indicated at 1 having spaced parallel side arms 2 which converge at their upper ends and are joined with an integral socket or ferrule portion 3 adapted to receive the end of the mop handle 4. A cross bar 5 is formed integrally as by casting with the frame 1 and extends between the side arms 2 at points spaced from the lower ends of the side arms. The cross bar 5 has an enlarged central portion 6 with a threaded aperture 7 formed therein for receiving the thumb screw 8.

The inner or opposed faces of the side arms 2 are provided below the cross bar 5 with inwardly projecting ribs 9 forming guide rails for a clamp bar 10. The ends of the clamp bar 10 have semi-cylindrical grooves 11 formed therein for receiving the ribs 9 to retain and guide the clamp bar between the side arms 2. The ribs 9 terminate as at 91 short of the lower ends of the side arms and the side arms are provided

2

with transversely aligned apertures 12 for receiving the mop holding rod 13. The under surface of the clamp bar 10 has a semi-cylindrical groove 14 formed therein and arranged to nest over the holding rod 13 and tightly clamp the mop 15 to the holding rod as illustrated in Fig. 2. The center of the clamp bar 10 is provided with an upstanding boss 16 engageable with the lower end of the thumb screw 8.

One or both of the side arms 2 have a notch 17 formed therein extending radially from the aperture 12 as is most clearly shown in Fig. 4 and the holding rod 13 is provided with a locking pin or lug 18 which extends radially from the holding rod and is arranged to pass through the notch 17 when the holding rod is inserted in the side arms. A head 19 is formed on the holding rod for manipulating the rod and limiting its position on the side arms 2.

With the construction described my thumb screw and clamp bar may be backed off and my holding rod removed to place the folded center of the mop between the ends of the side arms. The holding rod may then be inserted in the holes 12 between the folds of the mop and locked in place by rotating the lug 18 out of registry with the notch 17. The thumb screw may then be turned to clamp the clamp bar against the mop and the holding rod.

When the mop is placed in the frame dry as is the usual case and the thumb screw tightened as much as is conveniently possible with the thumb screw, later wetting of the mop will cause it to swell further tightening the mop. The wet mop may be quickly and easily released by turning the head 19 and rod 13 to register the lug 18 with the slot 17 and withdraw the rod. The rod will slip out easily even if the threads of the thumb screw have been tightly jammed by swelling of the mop.

I have thus described a highly practical embodiment of my mop head so that others may reproduce the same without further description.

Having thus described my invention, what I claim as new and desire to secure by Letters Patent is:

1. A mop head comprising a rigid frame having parallel side arms extending from a handle receiving ferrule and having a cross bar extending between and connected to said arms intermediate of the ends thereof, said cross bar having a threaded aperture formed therein, guide ribs formed on the opposed faces of said arms below said cross bar, a clamp bar having notched ends slidably received on said ribs, a thumb

screw extending through said threaded aperture and engageable at its lower end with said clamp bar, the ends of said arms having aligned holes formed therein, one of said holes having a radially extending notch disposed adjacent to one side of the rib on the arm in which said notch is formed, a mop holding rod removably positioned in said holes, said rod having a lug thereon slideable through said notch in said arm, and a knob on one end of said rod spaced from said lug whereby said knob and said lug will engage oppositely facing surfaces on said frame when said lug is turned out of registry with said notch to prevent axial movement of said rod.

2. A mop head comprising a frame having parallel side arms extending from a handle receiving portion and a cross bar extending between and connected to said arms intermediate of the ends of said arms, a clamp bar interlockingly engaging said arms and being slideable longitudinally therealong below said cross bar, adjustable screw means threadingly engaged with said cross bar and axially bearing unconnectedly against said clamp bar, the ends of said arms having transverse aligned holes formed therein, one of said holes having a radially extending notch, a mop holding rod positioned in said holes and axially

removable therefrom and rotatable therein, said rod having a lug arranged to pass through said notch and be rotated into rod locking engagement with the arm in which said notch is formed, and a knob on one end of said rod spaced from said lug whereby said knob and said lug will engage oppositely facing surfaces on said frame when said lug is turned out of registry with said notch to prevent axial movement of said rod.
